Dec. 1240

Washington D. Gilroy, of Philadelphia, Pa.
Letters Patent No. 1240. Dated April 24, 1860

The schedule referred to in these Letters Patent and making part of the same.

To all whom it may concern,

Be it known that I, Washington D. Gilroy, of the City of Philadelphia and State of Pennsylvania, have invented or produced a new and original Design for a Paint-Brush; and I do hereby declare that the following is a full and exact description of the same, reference being had to the annexed drawing making a part of this Specification, and to the letters of reference marked thereon, —

The object of this design is the production of a sheet-metal vessel, suitable for the purpose of "putting up" white lead or other paints ground in oil, which will serve as a "trade mark".

It consists of a sheet metal case, of a cylindrical form ornamented with certain plain surfaces, grooves or corrugations, and end mouldings, as hereinafter described.

In the drawing A. A. represent the plain surfaces; B. B. the grooves or corrugations; and C. C. the end mouldings.

The plain surfaces (A) and the apices of the convex parts (D), between any two of the grooves (B), are on a straight longitudinal line with each other.

The grooves (B) are each of like depth and form, and the convex parts between any two of them, are, also, each a reversed counterpart, both in depth and form, of the said grooves (B), both being of the form seen in the figure. Eight of these grooves are arranged together midway between the two ends of the vessel, and two, respectively, near the ends, the plain surfaces (A. A.) being between the middle series and the end

grooves, (B), respectively, as seen in the drawing.

The edges of the end plates of the vessel lap over on the periphery so as to produce around each end of the cylinder, the projecting moulding, (C), of the form shown in the figure.

What I claim herein as my invention or production, and desire to secure by letters patent, is

A vessel of the cylindrical form described, whose periphery is ornamented, with the plain surfaces, (A), grooves, (B) and mouldings, (C), arranged in relation to each other, as set forth, as a new and original design for a paint-vessel.
